UNITED STATES PATENT OFFICE

LESLIE A. SCHURR AND FLOYD BRECKENRIDGE, OF BRECKENRIDGE, MICHIGAN

WASHING MACHINE

Application filed March 16, 1929. Serial No. 347,643.

This invention relates to washing machines of that type in which there is set up a circulation of hot water while the machine, with fabrics therein to be cleaned, is in position over a heating element.

One of the objects of the invention is to provide a novel form of agitator which can be actuated from time to time for the purpose of changing the positions of the fabrics being cleaned, the construction of the agitator being such as to permit easy withdrawal from the fabric following the cleaning operation.

Another object is to provide a machine of this character having novel means therein for setting up a circulation of heated water, the water being distributed in several directions into the fabrics, thereby to expedite the cleaning operation.

A further object is to provide a structure that can be made at low cost and which is free of parts likely to tear or otherwise injure the contents.

With the foregoing and other objects in view which will appear as the description proceeds, the invention resides in the combination and arrangement of parts and in the details of construction hereinafter described and claimed, it being understood that changes in the precise embodiment of the invention 30 may be made within the scope of what is claimed without departing from the spirit of the invention.

In the accompanying drawings the preferred form of the invention has been shown.

35 In said drawings,

Figure 1 is a vertical transverse section through the complete machine.

Figure 2 is a top plan view.

40 Figure 3 is a section on line 3—3, Figure 1. Figure 4 is a horizontal section through a portion of the device showing the base of the header positioned for easy removal.

Figure 5 is a top plan view of the agitator, its handle being removed.

45 Figure 6 is a side elevation of the base disk or header and a portion of the distributing nozzle extending therefrom.

Referring to the figures by characters of reference, 1 designates a cylindrical container 50 which can be made of any suitable metal.

The upper end of this container is formed with an annular enlargement 2 providing a seat 3. Secured to the container at diametrically opposed points and preferably at the normal water level are handles 4 whereby the structure can be easily carried.

55 A lug 5 is extended a short distance inwardly from the periphery of the annular enlargement 2 and affixed or extended outwardly from said enlargement at a point diametrically opposite the lug are ears 6. Pivotedly mounted between these ears is a clip 7.

60 A concavo-convex cover 8 is adapted to rest at its margin on the seat or shoulder 3 and is provided, at its center, with a sleeve 9 having a flange 10 riveted or otherwise fastened on the cover. This sleeve is formed with a central bore 11 for the reception of a pin 12 provided with an angular end 13. 65 This angular portion is adapted to fit in a corresponding opening formed in one end of a crank arm 14, said crank arm being held in position by a nut 15 secured to the angular end 13 by a screw 16 or by any other suitable means. A spacing collar or washer 17 can 70 be interposed between sleeve 9 and the fastened end portion of the crank arm 14.

75 One end of the pin 12 projects into a socket 18 formed in a head 19, the said pin being attached to the head by means of a rivet 80 or the like extending diametrically therethrough. Diverging from the lower portion of the head 19 are agitating arms 20 which curve laterally and downwardly and terminate in knobs 21.

85 The cover 8 is adapted to be placed in position by inserting its margin under the lug 5. Clip 7 can then be sprung downwardly into engagement with the marginal portion of the cover at a point diametrically opposite the lug 5. Thus the cover will be held firmly on its seat with the agitating arms 20 supported within the container.

90 For the purpose of insuring a proper circulation and distribution of the cleansing fluid, there is provided a frusto-conical disk 22 having a fluted depending apron 23 at its margin adapted to rest on the bottom of the container. This apron is spaced at its upper end from the wall of the container so that 100

water is thus free to flow downwardly between said wall and the apron and under said apron into the space beneath the header formed by the disk 22. At diametrically opposed points the said header or disk is formed with notches 24.

Diametrically opposed retaining lugs are extended inwardly from the wall of the container near the bottom and when the disk or header 22 is lowered into the container the notches 24 can be arranged to pass the lugs. Thereafter, by giving a slight rotation to the disk or header 22, the notches can be moved from under the lugs and said lugs thus caused to lap the disk or header 22 and hold it against displacement relative to the container. In Figure 3 the disk or header 22 has been shown secured in position, while in Figure 4 a portion thereof has been illustrated in position for withdrawal from the container.

Header 22 has a desired number of annular channels or grooves 26 constituting gutters in which sediment can accumulate. A collar 27 is extended upwardly from the central portion of the header and into the large or lower end of a tapered nozzle 28. The upper end of this nozzle is adapted to be closed by a cap 29 fastened thereon in any suitable manner and formed in the nozzle are spaced longitudinal series of apertures 30.

In practice the container 1 is filled with a cleansing fluid, such as soapy water, up to a line approximately on a level with the handles 4. The fabrics to be cleaned are placed in this fluid, cover 8 is fastened in position, and the container placed over a heating element.

The cleaning fluid, when heated, will circulate by flowing downwardly between the header 22 and the wall of container 1 into the space under the header and thence upwardly into nozzle 28 from which it will be delivered in jets through the several longitudinal rows of apertures 30. As the fabrics are supported by the header and around the nozzle, these jets will be directed into the same, acting to separate dirt from them. From time to time the agitator 20 can be rotated by means of the crank arm 14, thereby shifting the fabrics within the container so that portions thereof not previously exposed to the direct action of the jets will be brought to position where they can properly be acted upon.

Following the cleaning operation the cover 8 can be removed by springing the clip 7 therefrom and obviously the agitating arms 20 will withdraw freely from the engaged fabrics when the cover is lifted. The channels or gutters 26 will act as traps for holding any sediment gravitating within the container.

The annular enlargement at the top of the

container 1 not only provides a seat for the cover but also serves to prevent the container from overflowing.

What is claimed is:

1. The combination with a container and agitating arms mounted for rotation within the container, of a frusto-conical member removably mounted in the lower portion of the container, an annular apron depending from said member and cut away to afford communication past the margin of said member between the container and the space below the conical member, said member having a concentric gutter therein between its upper and lower portions, an upwardly tapered apertured nozzle carried by the upper portion of the conical member and extending between the agitating arms. 70 75 80

2. The combination with a container and downwardly diverging arms mounted for rotation therein, of a conical member constituting a header detachably mounted in the lower portion of the container, a downwardly flared annular apron depending from the header and engaging the bottom of the container, said apron being cut away to provide means for communication between the container and the space beneath the header, there being an annular groove in the header constituting a gutter, a tapered apertured nozzle extending upwardly from the middle portion of the header and between the arms. 85 90 95

3. In a washing machine the combination with a container, of a conical header supported in the bottom portion thereof, an annular apron depending from the margin of the header and cut away to afford communication between the container and the space under the header, said apron also constituting means for holding the header spaced from but concentric with the container, a perforated nozzle extending upwardly from the middle portion of the container, means formed in the header for trapping sediment flowing downwardly from the center of the header toward the margin thereof, and agitating means mounted to move about the nozzle. 100 105 110 115

In testimony that we claim the foregoing as our own, we have hereto affixed our signatures.

LESLIE A. SCHURR.
FLOYD BRECKENRIDGE.
